UNITED STATES PATENT OFFICE.

JOSEPH BULLOCK, OF COHOES, NEW YORK.

COAL AND ASH SIFTER.

SPECIFICATION forming part of Letters Patent No. 249,582, dated November 15, 1881.

Application filed September 24, 1881. (No model.)

To all whom it may concern:

Be it known that I, JOSEPH BULLOCK, of the city of Cohoes, in the county of Albany and State of New York, have invented a new and Improved Coal and Ash Sifter, of which the following is a specification.

Figure 1 is a vertical section of my device on the line *z z*, Fig. 2, and designed to show the relative position of the inclined sieve, chute, and chambers underneath the sieves. Fig. 2 is a similar view on the line *y y*, Fig. 1.

The object of my invention is, by the combination and arrangement of two or more fixed inclined sieves, inclosed as set forth, in operation by gravity acting on the particles, to separate and clean coal and ashes, &c., and to conduct the same into their respective drawers. This I accomplish by the inclined sieves placed relatively to each other as indicated, and by inclosing them in casing and chute, as herein-after described.

The casing I is made of wood or other material, with cover K, drop-door A, supported by the receding catch *j*, and such door has metallic springs or spirals *b*, adjusted at or near the hinge C, intended to force back the drop-door to its closed condition when released of its load. At the bottom of the narrower part of the casing are extended shoulders I', which are provided to cover and guide the drawers G and H.

The bottom chamber of the sifter is divided into two divisions by the partition-plate O, which plate extends across the chamber, leaving a space which is filled up by the entrance therein of the chute F, as seen in Fig. 1. The bottom of the chute is a metallic sieve of the same width as the chute, extending diagonally across the vertical chamber, and at an angle of about forty-five degrees with the side of the casing.

Adjusted transversely to the upper end of the chute is the metallic sieve D, which rests at about an angle of forty-five degrees with the vertical side of the casing, leaving a space above for the swing of the drop-door A, which is hinged to the side of the casing, and this door is re-enforced and forced backward into its first position, when released of its load of coal, by the metallic spirals *b*, adjusted at or near the hinge C.

The catch *j* holds the door in position for the load, or when a continuous flow of the ma-

terial is desired it is left open. The metallic sieve D is soldered into position, as seen at *n*, 55 or the same is inserted in a suitable groove, if sieves of different apertures are desired, through a swing-door made in the casing.

As will be seen in the figures, and as indicated by the arrows, the finer particles, in their descent, pass into the drawer H, as shown by the arrows *v*, while the coarser particles gravitate down over the first and second sieve, through the chute F, into the drawer G, as shown by the arrows *x*.

To facilitate the passage of the ashes or finer particles between the angle formed by the chute and side of the case, I form a wedge-shaped protuberance at P, Fig. 1, to guide the particles through passages *m* at the side of the chute, 65 as seen in Fig. 2.

In operating my device additional sieves, placed relatively to each other as indicated, may be used, while, if the drop-door is left open, coal or other material admitted in a continuous flow will gravitate downward and be effectually screened, and the coarser and finer particles separated into their respective chambers.

My device may also be useful and adapted 80 to the screening of gravel and sand from a bank from which the material in continuous flow is allowed to gravitate downward over the inclined sieves and the particles separated into their respective chambers, as indicated. 85

As will be seen in the drawings and accompanying specification, the process of screening and separating the coarser and finer particles requires no motive power or artificial movement of the sieves, as in the use of the ordinary 90 sieves.

What I claim, and desire to secure by Letters Patent, is—

An improved coal and ash sifter with the following elements in combination with the 95 casing, viz: a drop-door, A, held in position by catch *j* and supporting-spirals *b*, two or more inclined sieves, adjusted as shown, the latter inclosed in a chute which rests on partition-plate O, with coal and ash drawers, all arranged 100 substantially as described, and for the purpose set forth.

JOSEPH BULLOCK.
